FREDERICK B. WALTER, OF WABASH, INDIANA, ASSIGNOR TO B. WALTER & CO., OF WABASH, INDIANA, A CORPORATION OF INDIANA

TABLE LOCK

Application filed May 25, 1928. Serial No. 280,441.

My invention relates to improvements in table locks for locking the sections of extension tables.

It has for one of its objects the provision of a simply constructed lock which, when manipulated to unlock the table sections, will at the same time partially separate the sections so that they may be more easily drawn apart.

10 For the purpose of disclosing my invention I have illustrated one embodiment thereof in the accompanying drawings, in which—

Fig. 1 is a bottom plan view of a portion of two table sections illustrating my lock applied;

Fig. 2 is a similar view showing the lock thrown to open position, and

Fig. 3 is a perspective view of a type of table to which my lock may be applied.

20 In the embodiment illustrated the table, as is usual, in tables of this character, comprises the two separable sections 1 and 2 which may be separated to receive a series of leaves.

25 On one of the sections I provide a keeper 3 which has at one end a down turned keeper lip 4 and is secured to the table by suitable screws 5.

The latch is mounted on the opposite section, preferably on a base plate 6, which is secured to the section by means of screws 7. This base plate is provided with a central pivot stud 8 on which is pivotally mounted a lever 9 provided intermediate of its end

30 with a latch hook 10 the outer face 11 of which is rounded. The hook overhangs an extension face 12 of the lever and the latch is maintained in locking position by a coil spring 13 one end of which is engaged in a lug 14 struck up from the plate 6 and the other end of which is engaged in an ear 15 on the lever. For preventing the spring from biasing the latch past its normal latching position, an ear 16 is adapted to strike a sta-

40 tionary lug 17 also struck up from the plate 6. With the parts in normal position as the two sections of the table are moved toward one another the keeper lug 4 striking the cam surface 11 will rock the lever on its pivot

45 50 permitting the hook to slide past the keeper.

As soon as the hook end passes the keeper the spring 13 tends to rotate the hook back of the keeper thus locking the two sections of the table together. When it is desired to release the two sections the end 18 of the lever 55 is manipulated to throw the hook 10 out of engagement with the keeper and this movement at the same time causes the edge 12 to move into engagement with the keeper forcing the two sections of the table apart. 60

I claim as my invention:

In an extension table having opposed sections, a keeper on one of said sections, a plate secured to the other of said sections, a lever pivoted on said plate and having an edge 65 parallel with the mating edges of the table and movable into engagement with the keeper by the rocking of the lever, a latch hook on said lever having a latching face overhanging and extending parallel with said lever edge, the opposite face of said hook being cammed to engage the keeper and rock the lever, suitable members on the lever and a stop lug struck up from said plate for engaging said members and limiting the movement of said lever, and a spring connecting said lever to said base to urge the same to a position with its edge lying parallel to the mating edges of the table. 70 75

In witness whereof, I have hereunto set my hand at Wabash, Indiana, this 17th day of May, A. D. one thousand nine hundred and twenty eight. 80

FREDERICK B. WALTER.
